UNITED STATES PATENT OFFICE.

HAROLD S. WEBBER, OF NEW YORK, N. Y., ASSIGNOR TO CROSS METAL PRODUCTS COMPANY, OF NEW YORK, N. Y., A CORPORATION OF NEW YORK.

MACHINE FOR MAKING METAL ARTICLES.

Application filed April 17, 1919. Serial No. 290,690.

To all whom it may concern:

Be it known that I, HAROLD S. WEBBER, a citizen of the United States, and resident of the borough of the Bronx, county of the Bronx, and city and State of New York, have invented certain new and useful Improvements in Machines for Making Metal Articles, of which the following is a specification.

10 The present invention relates to improvements in machines for making metal articles, the particular embodiment disclosed herein being adapted for the manufacture of the male portion of a snap fastener. An object 15 of the invention is to provide a machine capable of quantity production, and in which the articles formed will be uniformly perfect.

To this end, I propose to provide improved forming means and further to provide an improved head shaping means to the end that the article formed will be free from ridges and when produced in quantities will be uniformly perfect and identical in shape. 25 A still further object is to provide improved feeding means for feeding the material from which the articles are made through the machine.

With these and other objects in view, an embodiment of my invention is shown in the accompanying drawings and this embodiment will be hereinafter more fully described with reference thereto and the invention will be finally pointed out in the 35 claims.

In the accompanying drawings:

Figure 1 is a plan view of the present disclosed embodiment of my invention;

Figure 2 is a vertical sectional view 40 through the bed plate and showing in elevation the parts of the machine disposed upon the rearward portion thereof;

Figure 3 is a vertical sectional view taken along the line 3—3 of Figure 1;

Figure 4 is a vertical sectional view taken 45 along the line 4—4 of Figure 1;

Figure 5 is a detail view in elevation of the shell stripper.

Figure 6 is an enlarged view in vertical 50 section of the central part of the machine as shown in Figure 2, the transfer arm being in another position from that shown in Figure 2;

Figure 7 is an enlarged horizontal sectional view through the dies and punches forming a part of the machine;

Figure 8 is an enlarged longitudinal vertical sectional view taken along the line 8—8 of Figure 1, showing the rim rolling and neck producing parts of the machine, the transfer arm being in the position indicated in Figure 6;

Figure 9 is a horizontal sectional view showing the parts in the position to roll the rim;

Figure 10 is a fragmentary view showing the parts in position to reduce the neck;

Figure 11 is a detail view of the metal strip feeder;

Figure 12 is a vertical sectional view of the strip feeder;

Figure 13 is a detail side view of the strip holding means adapted to operate alternately to the strip feeder;

Figure 14 is a plan view thereof with parts broken away;

Figure 15 is a view showing a portion of the strip;

Figure 16 is a plan view of the type of article formed by the present disclosed embodiment; and

Figure 17 is a cross sectional view thereof.

Similar reference characters indicate corresponding parts throughout the several figures of the drawings.

Referring more particularly to Figure 1 of the drawings, the machine comprises a bed plate 20 supported upon legs 20^a and provided at its rear side with a cam shaft 21, journaled in bearings 22 and 23 and adapted to be operated from any suitable source of power.

A bevel gear 24 is provided at the end of the shaft 21 which meshes with and drives a bevel gear 25 provided upon the end of a cam shaft 26 disposed at one end of the bed plate and journaled in bearings 27 and 28 and which in turn is provided at its other end with a bevel gear 29 which meshes with and drives a bevel gear 30 provided upon the end of a cam shaft 31 disposed at the forward side of the bed plate and journaled in bearings 32 and 33. These shafts 21, 26 and 31 are simultaneously and equally driven.

The strip of material from which the articles are formed and indicated by the dot

100

105

and dash line Figure 1, is fed intermittently across the machine by means hereinafter more fully referred to and is disposed on edge, that is, it is in a vertical plane at right angles to the bed plate 20. The strip is first drawn through a stationary die head (Figs. 3, 6 and 7) consisting of a horizontal base 34 secured to the bed plate 20 by bolts 35 and provided at its forward edge with an 10 upstanding face plate 36 rigidly supported at its rear by reinforcing webs 37, the said plate being provided at its rear side and adjacent its upper end with an enlargement 38 having therein a plurality of spaced 15 cylindrical pockets 39, in which are disposed a succession of head forming reducing punch dies 40, adjustable by means of adjustment screws 41 disposed in the portion 38 bearing against the inner end of the dies 20 and securely held by set screws 42 extending downwardly in the plate 36 and bearing upon the upper surfaces of the dies. The heads 40^a upon the dies, are of gradually decreasing size as is usual in such metal 25 shaping dies. The strip of metal passes in front of the dies through a stripper comprising a plate 43 provided with a plurality of apertures 44, in which the projecting ends of the dies are slidably disposed, the said 30 plate having at its front side a pair of spaced guide bars 45 and 46 secured thereto by screws 47, the said bars being provided with opposed flanges 48 and 49 respectively having arcuate cut-outs 50 in 35 register with the apertures 44 and which permit of the passage of the reciprocating portion of the dies hereinafter more fully referred to. The strip of material is disposed in the slot formed by the bars 45 40 and 46. The stripper is mounted upon studs 51, and is normally held spaced from the plate 36 by springs 52 disposed on said studs and having their ends respectively engaging the plate 36 and the plate 43, the latter plate 45 being provided with sockets 53 in which the said springs are seated.

In front of the stationary die head (Figs. 1 and 3), there is disposed upon the bed plate, a block 54 having in its upper side a slot 55 dovetailed in cross section and in which there is mounted to reciprocate a slide 56 also of dovetailed cross section and engaged at one side by a gib 57 adjustable by means of set screws 58. At the forward 50 end of the slide 56 there is provided a head 59 upon which there is secured by means of a holding plate 60 a plurality of female dies 61 being disposed in passages 62 in the said plate, and held in place by being 55 driven into the said passages, said dies being adapted upon forward reciprocation of the slide to enter the arcuate portions 50 of the stripper. The dies 61 are provided with 60 passages 63 provided with plungers 65 slid-

ably engaging the reduced portion of the 65 passages and flanged at their inner ends as at 66, the said flanged ends located in the enlarged portion of the passages and being engaged by springs 67 disposed in the said 70 enlarged portion of the passages. As the slide is reciprocated forwardly, the dies 61 are engaged with the metal strip forcing the stripper toward the plate 36 and causing the heads 40^a to impress the strip forming a plurality of heads or projections thereon, 75 the first die producing a relatively large head from the flat strip, while the other dies gradually reduce this head to its finished shape as indicated in Figure 7. As the slide is reciprocated rearwardly, the stripper 80 resumes its normal position removing the metal strips from the heads 40^a, while the spring pressed plungers 65 insure positive and immediate disengagement of the struck-up heads from the passages of the dies 61 85 into which they have been forced, so that the strip is entirely free to be fed through the machine.

Reciprocation is imparted to the slide by means of an elbow lever 68, pivoted at 69 in a pocket 70 at the rear of the block 54 and provided at the end of its short upstanding arm with a socketed portion 71, engaging a driving stud 72 adjustably disposed in a recess 73 of the slide, the said 90 stud having a flat portion 74 which engages the under side of the recessed portion of the slide and is provided with a threaded shank 75 projecting upwardly through a longitudinal slot 76 in the slide, a nut 77 and washer 78 disposed upon the shank 95 adapted upon being tightened against the upper surface of the slide to fix the position of the said stud. The stud may be adjusted in the slot 76 by means of a screw 79 engaging a threaded hole 80 transversely through the shank 75, and provided with a projecting knurled head 81, the said screw being held against longitudinal movement by means of a pin 82 engaging an annular 100 groove 83 therein. The long arm of the lever 68 which projects rearwardly and is inclined upwardly is provided at its end with a roller 83 engaging the groove 84 of a cam 85 mounted upon the shaft 81. 105

At the side of the stationary die head, there is secured by bolts 86, a block 87 having at its upper end an open slot 88 through which the metal strip passes. In the front side of the block, there are provided three holes 89 in which there are slidably mounted cutting punches 90 secured to the reciprocating head 59 by their flanged ends 91 and adapted upon forward reciprocation of the head to cooperate with a hardened die 92 110 set in a recess 93 of the block and provided with registering openings 94, to perforate the metal strip as indicated in Figure 15. 115

The particles removed therefrom drop through an opening 95 provided in the block, to a suitable receptacle therefor.

In spaced relation to the cutting punches 90, there is provided on the head 59 a blanking out punch 96, tubular in shape and having its flanged end 97 held to the head 59 by the plate 60. The said punch 96 projects through a passage 98 in the block 87 and is adapted upon forward reciprocation of the head to cooperate with an apertured cutting die 99 disposed in a recess 100 of the block to blank out the piece of metal destined to become the snap fastener part. A cylindrical passage 101 extends through the block being reduced in diameter relatively to the aperture of the die 99, a drawing die 102 being provided in the recess 100 beneath the die 99, the wall of the aperture 20 thereof being of smaller diameter than the wall of the aperture of the die 99 and rounded at its edge adjacent the die 99.

A plunger rod or punch 103 having its forward end disposed in the tubular punch 96 extends through a passage 104 in the head 59 and into a passage 105 in the block 54 where it is coupled as at 106 to a driving rod 107 slideable in the said passage 105, its projecting rear end being provided with a 30 rectangular bearing block 108, rotatable upon a transverse pin 109 and engaged by the forked upper end 110 of a lever 111 pivotally mounted at 112 in a bracket 113 secured to the bed plate, and provided intermediate its ends with a roller 114 engaging the cam groove 115 of a cam 116 mounted upon the cam shaft 31. The forward end of the rod 103 is provided with a socket 117 adapted to embrace the head formed in the metal strip, and as the piece of metal is blanked out of the strip as above pointed out, the plunger rod is projected forwardly, carrying the piece of metal into and through the passage 101, the tapered aperture of the plate 102, and reduced diameter of the said passage 101 causing an annular upturned rim to be formed thereon. By the continued movement of the plunger rod 103, the metal piece which is now in the form of a shell, is forced through the passage 101 and into an opening 118 in the end of a transfer arm or lever 119, the operation and function of which will be presently pointed out. In passing out of the passage 101, the shell engages a mechanical stripper (Figures 4, 5, and 7) which prevents the same from being drawn back into the said passage by the return movement of the rod 103.

This mechanical stripper is disposed in a recess 120 at the rear side of the block annularly surrounding the passage 101 and comprises a pair of opposed members 121 and 122 pivoted at 123 and 124 to a holding plate 125 set in the recess, the outer periph-

ery of the said members being spaced from the sides of the recess 120, and grooved as at 126, the said groove being engaged by a split circular spring ring 127, the said members being limited in their inward movement by engagement of their free ends. Segmental flanges 128 and 129 are provided respectively on the members 121 and 122 which have their inner sides concentric to and inwardly of the wall of the passage 101 and are rounded as at 130 adjacent the end of the said passage to provide guiding surfaces for the shell. The holding plate 125 is secured in the recess by means of pins 131 and 132 disposed in the block 87 and engaging diametrically opposed recesses in the periphery of the said plate. In operation, the movement of the shell from the passage 101 to the transfer arm will cause the members 121 and 122 to open, allowing passage 85 of the shell therethrough and as the shell passes out of the stripper, the said members close upon the plunger rod, stripping the shell therefrom as the plunger is withdrawn, the shell remaining in the opening 90 118 of the transfer arm.

Upon the bed plate 20, there is secured by bolts 133, a supporting member 134 having an upright portion 135 supported at its rear side by a reinforcing rib 136 and provided 95 with a projecting arm 137, having its under side spaced from the bed plate and extending behind the passage 101 of the block 87, one arm 138 of the transfer lever being disposed forwardly of the said projecting arm 100 137 and mounted upon a rock shaft 139 journaled in the said arm, the other arm 140 of the transfer lever being rearwardly of the arm 137 and also mounted upon the said rock shaft. The free end of the arm 140 is 105 pivotally connected at 141 to one end of a connecting rod or bar 142, the other end of which is pivotally connected to a lever 143 pivotally mounted at 144 upon a bracket 145, secured to the bed plate, and provided 110 intermediate its ends with a roller 146 engaging the cam groove 147 of a cam 148 mounted upon the shaft 26. As the cam 148 is rotated, the transfer lever is moved from the position indicated in Figure 2 to a position substantially 90° removed therefrom as indicated in Figures 6 and 8, carrying the shell disposed in the opening 118 from the first to the latter position. An adjustable stop screw 149 disposed in a supporting 120 plate 150 secured by screws 151 to the upper side of the arm 137, limits the upward movement of the transfer arm, while an adjustable stop screw 152 mounted in a supporting member 153 secured to the arm 137 by screws 125 154, limits the transfer arm in its downward movement.

In alignment with the opening 119 of the transfer arm in its lowered position (Figure 8) and rearwardly of the arm 137 there are 130

secured upon the bed plate by screws 155 at each side of an opening 156 formed in the bed plate, bearings 157 and 158 having aligned cylindrical bores or passages 159 therein in which is journaled a tubular spindle 160, provided at its forward end with a head 161 between which and the forward end of the bearing 158 there are interposed anti-friction ball bearings 162. Within the tubular spindle 160 there is slidably mounted a sleeve chuck member 163 and having a slot 164 engaged by a pin 165 passing through the spindle 160 and securing the same to a gear 166 mounted upon the spindle between the bearings 157 and 158 and meshing with a segmental rack 167, the hub 168 of which is rotatably mounted upon a shaft 169 supported in depending brackets 170 and 171 secured to the body of the machine. An arm 172 is provided on the hub 168 and is pivotally connected at 173 to one end of the connecting rod 174 pivotally connected at its other end as at 175 to a lever 176 pivotally mounted at 177 upon a bracket 178 secured by bolts 179 to the bed plate, and provided intermediate its ends with a roller 180 engaging the cam groove 181 of a cam 182 mounted upon the shaft 26. This cam is so shaped that during a portion of one cycle of operation of the machine, it operates through the segmental rack 167 and gear 166, to spin the spindle and the chuck sleeve first in one direction and then in the other, the function of which operation will be presently more fully pointed out.

At its rearwardly projecting end, the sleeve 163 is threaded as at 183 and has screwed thereto a pair of spaced collars 184 and 185 engaged by the forked end 186 of a laterally disposed arm 187 secured at the forward end of a reciprocating member 188 slidably mounted in a slot 189 of the block 190 secured to the bed plate and provided at its rear end with a roller 191 engaging the cam groove 192 of a cam 193 mounted upon the shaft 21. The function of this cam is to reciprocate the sleeve 163 in the spindle 160. The passage through the spindle is slightly enlarged at its forward portion as at 194 and at its end is provided with a flared portion 195 and within its enlarged portion the chuck sleeve is longitudinally trifurcated by means of slots 196, the end thereof being flared both exteriorly and interiorly as 197 and provided with inwardly projecting annular toothed portions 198 thereby forming gripping jaws adapted to contract as the sleeve is drawn inwardly to engage the flared end thereof with the flared portion 195 of the spindle, the said jaws being normally expanded and providing an opening or mouth in register with and substantially corresponding in size to the opening 118 of the transfer arm.

Within the bore of the sleeve 163 there is

provided an ejector rod 199, its rearwardly projecting end extending into a socket 200 formed in a slide 201 mounted to reciprocate in a slot 202 provided in the block 190, the said rod being provided within said socket 70 with a shoulder 203 engaged by a threaded bushing 200a screwed into the socket. The rod 199 is rotatable and at its end is disposed in an annular anti-friction thrust bearing 204, adjustable axially by means of 75 a set screw 205 bearing upon a spacing plate 206. At one side the slide 201 is provided with a roller 207 held in engagement with the periphery of a cam 208 mounted upon the shaft 21, by means of a spring 209 connected at one end to a pin 210 at the upper side of the slide and at its other end to an arm 211 secured to the bed plate.

The forward end of the rod 199 is slightly convex and is provided with a socket 212 85 in which there is disposed a plunger pin 213 slidable through a threaded bearing 214 screwed into the socket and engaged at its inner flanged end 215 by a spring 216, the end of the said spring being normally projected as indicated in Figure 9.

Forwardly of the transfer arm, there is provided upon the bed plate a block 217 provided with a longitudinal slideway 218 and having at its inner end an upstanding head 219 provided with a cylindrical passage 220 therethrough in axial alignment with the rod 199. A slide block 221 is disposed in the slideway 218 being held in place by gibs 222 and 223 extending over the slot and over 100 flanges 224 and 225 provided upon the block. A plunger rod 226 extends through a passage 227 in the block and also through a projecting tubular member 228 secured in a recess 229 of the block by a set screw 230, and slidably engaging the passage 220 through the head 219, the said rod and the block and tubular member 228 carried thereby, adapted to have independent reciprocatory movement, the latter by means of a transversely 110 disposed lever 231 pivotally mounted upon the bed plate at 232, and slidably engaging at its forked end 233, a turn-block 234 pivotally mounted upon the upper side of the block 221, while at its other end it has an 115 adjustable pivotal connection 235 with a link 236 pivotally connected at 237 to a slide member 238 mounted in a slideway 239, secured to the bed plate and provided at its projecting end 240 with a roller 241 engaging the cam groove 242 of a cam 243 mounted upon the shaft 31.

The rod 226 is secured at its outer end in a slide block 244 slidable in the slideway 218 by means of a set screw 245, the said slide block being provided at its projecting end 246 with a roller 247 engaging the cam groove 248 of a cam 249 mounted upon the shaft 31.

The end of the member 228 is recessed as 130

at 250 surrounding the end of the rod 226 which is slightly concave to a substantially similar extent to the convexity of the end of the rod 199, and is provided with a socket 5 251 for the reception of the head formed upon the article. In order to prevent too tight a hold upon the said head, the end of the rod 226 is split as at 252.

At the forward side of the support 135, 10 there is provided a T-slot 253 in which there is mounted a slide member 254, carrying a plate 255, longitudinally aligned with the slide by means of a rib 256 at its under side disposed in a groove in the slide, and secured 15 to the slide by means of a screw 257 passing through a longitudinal slot 258 therein and screwed into the slide, the said plate being longitudinally adjustable upon loosening of the screw 257, by means of an adjustable stop screw 259 mounted in a projecting boss 259^a provided upon the slide. The slide is forked as at 260 at its projecting end and is connected by a vertical pivot 261 to a lever 262 pivotally mounted at 263 upon 20 the bed plate and provided at its end with a roller 264 engaging the groove 265 of a barrel cam 266 mounted upon the shaft 21. 25 The plate 255 is cut out or recessed at its forward end as at 267 (Fig. 6) and above 30 and below the said recess there are loosely mounted upon studs 268 and 269 set in the plate, rollers 270 and 271 having their rounded peripheries in the same vertical plane and spaced from each other, these 35 rollers constituting reducing means for forming the neck upon the head of the article, as shown in Figure 17 and as will presently be more fully pointed out in describing the operation of the machine.

40 The metal strip is intermittently drawn through the machine by means of a reciprocating gripper comprising a slide 272 (Figs. 11 and 12) mounted in a channelled slideway member 273 and held therein by gibs 274 and 275 secured by screws 276 and projecting over the channel and over the flanged sides 277 and 278 of the said slide. From the base of the slide, there extends upwardly a pair of spaced side portions 279 and 280 45 connected by a cross piece 281 constituting one jaw of the gripping member and which engages the metal strip. The other jaw member consists of a V-shaped part 282 pivotally mounted at 283 within the side portions 279 and 280, and provided at the end of its upstanding portion with a jaw head 284 cooperating with the cross piece 281 to grip the metal strip. At its horizontal portion, the member 282 is engaged by 50 the rounded under side of a roller head 285 provided upon the end of a lever 286 transversely pivoted at 287 upon a U-shaped bearing 288 pivoted upon the bed plate, the shank 289 thereof extending through the bed

plate and being secured at the under side 65 thereof by a nut and washer 290, the said roller head being embraced laterally by projecting portions 291 and 292 provided upon the side portions 279 and 280.

The outer end of the lever 286 is provided 70 with a laterally disposed roller head 293 adjustable vertically by means of the threaded engagement of its screw shank 294 with the end of the lever, a lock nut 295 being provided upon the said shank. 75 The roller head 293 rests at its rounded under surface upon a cam 296 adapted to raise and lower the lever to cause the jaws 80 to grip and release the metal strip, while at its upright sides the roller engages a cam surface 297 forming a part of the cam 296 and mounted upon the shaft 21. The roller is held in engagement with the said cam surface by means of a spring 298 connecting the lever with the supporting head 85 235, the said cam surface adapted to impart swinging movement to the gripper in a direction to draw the metal strip through the machine when the same is gripped by the jaw and to move free of the strip in the other direction, the jaws being open. The gripper is limited in its swinging movement by an adjustable stop screw 299 mounted in an end plate 300, secured to the slideway by screws 301, the said stop screw being fixed 90 in position by a lock nut 302.

Alternately cooperating with the reciprocating feeder or gripper, and adapted to hold the metal strip securely when the same is not being fed and to release it during 100 the feeding, there is provided adjacent the gripper a fixture 303 secured to the bed plate and provided with a stationary head 304 having a face plate 305 secured by pins 306 disposed in the head and projecting 105 from the face plate to form supporting guides for a movable gripping plate 307, between which and the face plate the strip passes.

A lever 308 pivotally mounted at 309 in a 110 bracket 310 secured to the bed plate, is provided at the end of its upstanding arm 311, with an adjustable screw 312 having a fixing nut 313 disposed therein and engaging the plate 307 between the pins 306. 115

At its outer end, the lever 308 is provided with a roller 314 engaging a cam 315 mounted upon the shaft 21 and adapted to swing the said lever to alternately grip and release the strip as above pointed out.

The operation of the machine from the point at which the shell is formed and placed in the transfer arm as above pointed out, is as follows:

The transfer arm moves from the position indicated in Figure 2, to the position indicated in Figure 6, carrying the shell

into alignment with the rod 199 and the plunger 226, the slide blocks 221 and 244 moving toward the transfer arm so that the die 228 and the plunger rod 226 are 5 brought against the forward surface of the transfer arm and at the same time the rod 199 moves toward the plunger 226 forcing the shell from the opening 118 of the transfer arm into the recess 250 of the die 228 10 thereby rolling over the rim formed upon the shell and dishing the shell as indicated in Figure 9. The rods 199 and 226 remain in contact with the article being formed and simultaneously move rearwardly, carrying 15 the shell back through the opening 118 and into the end of the chuck sleeve 163 which at this point, starts to move rearwardly with the rod 199 so that the flared portion 197 thereof engages the flared end 195 of 20 the spindle 160, causing the jaws of the chuck member to close upon the article thereby securely holding the same as shown in Figure 10, the rod 226 being thereupon withdrawn. The head formed upon the 25 article is now in alignment with the rollers 270 and 271, and the slide 254 moves inwardly so that the rollers engage over the said head as indicated in Figure 10, and simultaneously with this engagement, the 30 spindle 166 together with the chuck sleeve and the rod 199 are caused to spin first in one direction and then in the other by operation of the segmental rack 167 and according to the amount of pressure with 35 which the rollers 270 engage the head, a corresponding neck is spun upon the head. These rollers are loosely mounted, and the diameter of the neck formed is normally greater than the distance between the periphery of the said rollers so that by adjusting the position of the plate 255 by 40 means of the stop screw 259, the size of the neck may be accurately regulated and any wear upon the rollers may be taken 45 up in this manner. When the spinning operation is completed, the transfer arm having previously been moved to its raised position (Figure 2), the rollers are withdrawn and the chuck sleeve is projected so 50 that the jaws are opened to release the article which is thrown out by a forward movement of the ejector arm 199, the cam 208 being provided with a small rise 208^a which imparts this last ejecting movement 55 to the said rod, the article upon being removed dropping through an opening 316 of the bed plate into a suitable receptacle. The plunger pin 213 provided in the rod 199 insures removal of the article from the 60 end of the said rod, as the compression upon the article might from the adherence of grease or other substance upon the same, cause it to stick to the end of the rod 199.

I have illustrated and described a pre-

ferred and satisfactory embodiment of my 65 invention, but it is obvious that changes may be made therein within the spirit and scope thereof as defined in the appended claims.

I claim:

1. A machine for making metal articles 70 comprising means for feeding strips of stock from which the articles are to be made through the machine, means for initially forming heads upon the articles while still in the strip, punching means to remove the 75 headed articles from the strip and having means associated therewith for rolling the rims of the articles, rotary means adapted to subsequently receive the headed and rim-rolled articles and for rotating the same, 80 and means to engage the inner portions of the necks of the heads during the rotating operation to reduce such necks.

2. In a machine of the character described, 85 means for feeding a strip of material on edge, means for cutting pieces therefrom for forming an article of manufacture from said strip, means for performing certain operations upon said pieces, means removed therefrom for performing other operations thereon, and a pivoted transfer arm having to and fro movement in a vertical plane for carrying said pieces from said first mentioned means to said other means.

3. A machine for making metal articles 90 comprising feeding means adapted to draw the stock in the form of a strip through the machine, means for operating upon the strip to form heads upon the articles while still in the strip, punching means for cutting the 100 articles out of the strip and having die means associated therewith for rolling the edges of the articles, other means for shaping the articles and for spinning a reduced neck inwardly of the outer end portions of the 105 heads, and transfer means for moving the article from said punching means to said last named means.

4. In a machine of the character described, 110 means for feeding a strip of material, means for cutting pieces therefrom for forming an article of manufacture from said strip, means for forming a head on said pieces before cutting of said pieces from said strip, means adapted to receive one of said pieces with 115 said head, means adapted to revolve said last mentioned means, and means adapted to engage said head during said revolving to spin said head to a predetermined shape.

5. A machine for making metal articles 120 comprising feeding means for the stock strip, head forming means adapted to operate upon the strip before the articles are cut therefrom, slot punching means also operating upon the articles while in the strip to cut 125 slots about the heads, punching means for cutting out the headed and slotted articles from the strip, a die associated with the

- punching means for simultaneously rolling an edge thereof, a transfer mechanism positioned to receive the article from said die means by action of the punching means, and 5 other means for shaping the article and for producing a reduced neck inwardly of the head portion, said transfer mechanism adapted to convey the article from said punching means to said last named means.
- 10 6. In a machine of the character described, means for feeding a strip of material, means for forming a shell shaped article of manufacture therefrom comprising a stationary die head, a tubular blanking punch carried 15 by said reciprocating die head adapted to cooperate with said blanking die to cut a piece of material from said strip, said stationary die head being provided with a reduced passage in axial alignment with said blanking die, a drawing punch adapted to have independent reciprocatory movement relatively to said blanking punch and adapted to carry said piece of material blanked out by said blanking dies through said reduced passage 20 to form a shell rim thereon, a pivoted transfer arm having to and fro movement, and provided with an opening disposed in axial alignment to said blanking and drawing means in one position, said drawing punch 25 adapted to insert said article in said opening of said transfer arm, means for rolling over said rim formed upon said shell, said transfer arm adapted to carry said shell from said blanking and drawing means into operative relation with said rim rolling means.
7. In a machine of the character described, means for feeding a strip of material, means for forming a shell shaped article of manufacture therefrom comprising 30 a stationary die head, a tubular blanking punch carried by said reciprocating die head adapted to cooperate with said blanking die to cut a piece of material from said strip, said stationary die head being provided with a reduced passage in axial alignment with said blanking die, a drawing punch adapted to have independent reciprocatory movement relatively to said blanking punch and adapted to carry said piece of 35 material blanked out by said blanking dies through said reduced passage to form a shell rim thereon, a pivoted transfer arm having to and fro movement, and provided with an opening disposed in axial alignment to said blanking and drawing means in one position, said drawing punch adapted to insert 40 said article in said opening of said transfer arm, means for rolling over said rim formed upon said shell, said transfer arm adapted to carry said shell from said blanking and drawing means into operative relation with said rim rolling means.
- 45 8. In a machine of the character described, means for feeding a strip of material, means for forming a shell shaped article of manufacture therefrom comprising a stationary die head, a tubular blanking punch carried by said reciprocating die head adapted to cooperate with said blanking die to cut a piece of material from said strip, said stationary die head being provided with a reduced passage in axial alignment with said blanking die, a drawing punch adapted to have independent reciprocatory movement relatively to said blanking punch and adapted to carry said piece of material blanked out by said blanking dies through said reduced passage to form a shell rim 50 thereon, a pivoted transfer arm having to and fro movement, and provided with an opening disposed in axial alignment to said blanking and drawing means in one position, said drawing punch adapted to insert 55 said article in said opening of said transfer arm, means for performing a further operation upon said shell, stripper means in said passage of said drawing die comprising a pair of pivoted members having their inner periphery projecting within said passage, said members being slidable outwardly to permit passage of said shell therethrough into said transfer arm and adapted to prevent return movement of said shell upon 60 withdrawal of said drawing punch, said transfer arm adapted to carry said shell from said blanking and drawing means into operative relation with said means for performing a further operation upon said shell.
- 65 9. In a machine of the character described, means for forming a shell shaped article having a head thereon, means adapted to receive said article to roll over said rim, means adapted to transfer said article 70 from said forming means to said rim rolling means, means in axial alignment with said rim rolling means adapted to grip said article, means for revolving said gripping means, and means adapted to engage said head on said article during said revolving to spin said head to a predetermined shape.
- 75 10. In a machine of the character described, means for forming a shell shaped article having a head thereon, said article 75 being disposed on edge, means in a different horizontal plane adapted to receive said article to roll over said rim, a pivoted transfer arm having to and fro movement in a vertical plane and adapted to transfer said article from said forming means to said rim rolling means, means in axial alignment with said rim rolling means adapted to grip said article, means for revolving said gripping means and means adapted to engage said 80 punch, said transfer arm adapted to carry 85

- head on said article during said revolving to spin said head to a predetermined shape.
11. In a machine of the character described, means for forming a shell shaped article of manufacture having a rim and a central head extending in the same direction, means adapted to receive said article to roll over said rim upon the head side of said article, means in axial alignment with said rim rolling means adapted to grip said article, means for revolving said gripping means and means adapted to engage said head on said article during said revolving to spin said head to a predetermined shape.
- 15 12. In a machine of the character described, means for forming a flat article of manufacture having a head thereon, means adapted to receive said article to give to the same a predetermined non-flat shape, means adapted to transfer said article from said forming means to said last mentioned means, means in axial alignment with said last mentioned means adapted to grip said article, means for revolving said gripping means, and means adapted to engage said head of said article during said revolving to spin said head to a predetermined shape.
13. In a machine of the character described, means for forming an article of manufacture having a head thereon, means adapted to grip said article, means adapted to transfer said article from said forming means to said gripping means, means for revolving said gripping means, and reciprocating means having a pair of reducing rollers adapted to be moved into engagement with said head of said article during said revolving to spin said head to a predetermined shape.
- 40 14. In a machine of the character described, means for forming an article of manufacture having a head thereon, means adapted to grip said article, means adapted to transfer said article from said forming means to said gripping means, means for ro-
- tating said gripping means, and reciprocating means having a pair of reducing rollers in the same vertical plane and in the plane of rotation of said article, and having their peripheries spaced apart a distance less than the width of said head, said rollers adapted to be moved into engagement with said head to spin said head to a predetermined shape.
15. In a machine of the character described, means for forming an article of manufacture having a head thereon, means adapted to grip said article, means adapted to transfer said article from said forming means to said gripping means, means for rotating said gripping means and reciprocating means having a pair of reducing rollers in the same vertical plane and in the plane of rotation of said article, and having their peripheries spaced apart a distance less than the width of said head, said rollers adapted to be moved into engagement with said head to spin said head to a predetermined shape.
- 60
16. In a machine of the character described, means for forming a shell shaped article having a head thereon, means adapted to receive said article to roll over said rim, means adapted to transfer said article from said forming means to said rim rolling means, means in axial alignment with said rim rolling means adapted to grip said article, means for revolving said gripping means, and means adapted to engage said head on said article during said revolving to spin said head to a predetermined shape, and means adapted to eject said article from said gripping means.
